UNITED STATES PATENT OFFICE.

WILLIAM B. STOUT, OF DETROIT, MICHIGAN, ASSIGNOR TO PACKARD MOTOR CAR COMPANY, OF DETROIT, MICHIGAN, A CORPORATION OF MICHIGAN.

AIRPLANE.

Original application filed March 2, 1918, Serial No. 220,070. Divided and this application filed April 8, 1921. Serial No. 459,641.

To all whom it may concern:

Be it known that I, WILLIAM B. STOUT, a citizen of the United States, and residing at Detroit, Wayne County, State of Michigan, have invented certain new and useful Improvements in Airplanes, of which the following is a specification.

The present application which is a division of my application, Serial No. 220,070, filed March 2, 1918, relates to airplanes and more particularly to the ribs thereof.

The principal object of the invention is to provide a rib structure which can be manufactured with a minimum of time and labor and which has maximum strength for a given weight. Other objects and features of the invention will be apparent from the description taken in connection with the drawings, in which:

Figure 1 is a perspective view of a metal rib constructed in accordance with the present invention and shown as having a bendable strip attached to the lower member thereof together with means for flexing this latter member to change the camber of the rib;

Figure 2 is a perspective view similar to Figure 3 showing a similar form of rib but with the upper member thereof provided with a bendable strip;

Figure 3 is a sectional elevation taken substantially on the line 3—3 of Figure 1;

Figure 4 is a sectional elevation taken substantially on the line 4—4 of Figure 2;

Figure 5 is a sectional elevation taken substantially on the line 5—5 of Figure 2;

Figure 6 is a side elevation of a rib similar to that shown by Figure 1 except that the bendable strip is supported at three points and extends substantially from end to end of the rib;

Figure 7 is a side elevation of a stamped or pressed out metal rib; and

Figure 8 is a sectional elevation taken substantially on the line 8—8 of Figure 7.

Referring to Figure 7 I have shown a novel form of rib or beam which is designed to be stamped or pressed out from sheet metal. As illustrated, this rib is of channel cross section and comprises the top member or flange 33 and the bottom member or flange 34 connected by the web 35 and preferably integral with the web. This web is formed with the flanged apertures 36, the

flanges 37 of which are preferably struck out 55 from the web and interposed between and lie substantially in the plane determined by the top and bottom flanges and constitute reinforcing members or rings. As shown, these reinforcing members or rings are in 60 contact with the flanges and with one another. In order to increase the rigidity and strength of the beam the parts are secured together at these points of contact in any suitable manner as by welding. Of course 65 the top and bottom members and the entire beam are constructed to give the proper camber to the rib. As is obvious, a rib or beam constructed in this manner is exceedingly strong and rigid for the amount of 70 material or weight used.

In Figures 1, 2, 3, 4 and 5 I have shown a rib of the type just described, but with the added feature of means for changing the camber thereof. Referring now to Figure 75 1 it will be seen that the rib proper is of channel shape in cross section and is intended to be formed by being stamped or pressed out from sheet metal. It comprises the top flange or member 38 and the bottom member 39, connected by the web 40, which is formed with the flanged apertures 41. These latter flanges 41' constitute reinforcing members or rings and are interposed between the top and bottom members and welded 80 thereto and to each other. Preferably the flanges 41' are struck up from the web. As clearly shown in Figure 1 the front portion 85 of the lower member 39 is offset toward the top member 38, thus forming a recess. At the ends of this recess, socket pieces 42 and 43 are provided and a bendable strip 44 is arranged with its ends mounted in said sockets. The forward end of the strip is secured in the socket 43 by means such as a 90 pin 45 while the rear end is free to slide longitudinally in the socket 42. The rib is carried by a tubular spar 27 which extends through the same between the top and bottom members and which is formed with an aperture 28 through which extends a radial arm 30 carried by a tube 29 rotatively mounted in the spar. As shown, the spar is mounted in one of the apertures 41' being secured to the flange 44' in any suitable manner. The strip 44 carries a bracket or fitting 32 and a link 31 operatively connects the said bracket and the

80

85

90

95

100

105

arm 30 so that rotation of the tube 29 varies the curvature of the strip 44 thereby changing the camber of the rib.

Figure 2 illustrates a construction similar to that shown by Figure 1 except that the bendable strip is carried by the upper member of the rib. In this form of the invention the channel shaped stamped metal rib has its upper member 46 at the forward portion thereof offset towards the lower member 46' to thereby form a recess. At the ends of this recess the rib is formed with socket pieces 47 and 48 and a bendable strip 49 is mounted with its ends seated in the said socket pieces, one end as the front end being secured by a pin 48', the other end being free to slide in the socket 47. This strip intermediate its ends carries a bracket 32 and is adapted to be flexed in the same manner as described in connection with Figure 1.

As shown in Figure 3 the socket 42 may be formed by bending up an extension on the lower flange 39 and the socket 47 may be formed in a similar manner, as shown in Figure 4. Likewise the sockets 43 and 48 may be formed by bending up a piece integral with the rib as illustrated in Figure 5.

In Figure 6 I have illustrated a stamped metal rib having one of its flanges offset towards the other for the greater part of its length to form a recess in which is arranged a bendable strip supported at three points. Although the bendable strip may be attached to either the top or bottom member, I have shown only the latter form. The lower member 50 of the rib is offset towards the upper member 51, as shown, and adjacent the nose of the rib there is provided the socket piece 52, and at the tail end the socket 53. Midway between these two sockets is a support 54. The bendable strip 55 is mounted in these sockets and support, being held securely in the support 54 by a pin 56, but free to slide in the sockets 52 and 53. For the purpose of changing the camber of the rib I have shown the bracket 32 attached to the strip 55 at a point intermediate the socket 52 and support 54. This bracket 32 is the same as that already described and is adapted to be moved towards and from the rib by any suitable mechanism, preferably the same as described in connection with Figures 1 and 2. It will be observed that the movement of the bracket 32 will flex the strip 55 between the socket 52 and support 54 and will also cause an opposite curvature of the portion of the bracket between the support 54 and socket 53. The socket 52 and 53 and support 54 may be formed in the same manner as the sockets described above.

It is apparent that the connection between the rotatably mounted tube 29 and the bendable member of the rib may be made in various ways. As shown in Figures 1 and

2 the arm 30 may be struck up from the wall of the tube 29. For this purpose the arm is formed before assembling the parts and afterwards it is bent out through the aperture 28 to a position at right angles to the tube. The aperture 28 in the spar is of such dimensions that it permits the arm to be bent up and also allows the necessary angular movement of the same in the operation of the plane. 75

The rings 37 and 41' not only stiffen the web and resist torsional strains, but also act as arches in resisting bending of the rib vertically. Thus the added rigidity because of the rings is greater than if the same amount of metal were used in the plane of the web. Moreover the metal of the web bent up to form the portions of the flanges 37 and 41' that are adjacent the marginal flanges of the ribs, is farther from the neutral axis of the rib than if said metal remained in the plane of the web. Hence the moment of inertia of the cross section (such as shown in Figure 8) is increased, and the resistance to vertical bending also increased. This feature is clearly apparent from an inspection of Figure 8. If the metal forming flanges 37 were not pressed out but remained in the plane of the web 35, the moment of inertia of the section 95 would be less than that of the section of Figure 8, wherein the flanges 37 are disposed as far from the neutral axis of the beam as possible. 85

The rings or flanges 37 and 41' considered either with or without the web portions in effect constitute struts between the top and bottom members of the rib. 100

From the foregoing description it is apparent that I have provided ribs especially adapted for quantity and standardized production. The metal rib of this invention can be manufactured by automatic machinery, there being a minimum of hand labor required. Furthermore, if the rib is stamped out of sheet metal it can be produced in a fraction of the time required for the old style wooden rib. The tedious time-consuming steps of selecting and bending the wood, shaping the parts, gluing, etc., are entirely eliminated; also the period of a year or more required to season the wood. 110 115

The feature of changing the camber is not claimed herein, the same constituting part of the subject matter of my prior application, Serial No. 220,070. 120

Having thus described the invention what I claim as new and desire to secure by Letters Patent is:

1. A rigid metal rib for airplanes comprising top and bottom members and rigid reinforcing rings interposed between, in contact with and integrally joined to, and arranged in the plane determined by said members. 125

2. A rigid metal rib for airplanes com- 130

prising top and bottom members and rigid reinforcing rings interposed between, in contact with and joined to, and arranged in the plane determined by said members and also joined to each other.

3. A metal rib for airplanes comprising a web having a flange at the top and bottom edges thereof constituting top and bottom members, said web formed with flanged 10 apertures, the latter flanges being interposed between and welded to said members and acting to reinforce the same and stiffen the web.

4. A metal rib for airplanes comprising 15 a web having a flange at the top and bottom edges thereof constituting top and bottom members, said web formed with circular flanged apertures, the latter flanges being interposed between and welded to said members and acting to reinforce the same and stiffen the web.

5. As an article of manufacture, a metal beam of channel cross section having a web and top and bottom flanges, the web being 25 formed with a plurality of flanged apertures the latter flanges being interposed between and in contact with said top and bottom flanges and acting to reinforce said top and bottom flanges and stiffen the web.

30 6. As an article of manufacture, a stamped sheet metal beam of channel section having reinforcing members struck up from the web, interposed between and welded to the flanges thereof.

35 7. As an article of manufacture, a

stamped sheet metal beam of channel section having a series of circular reinforcing members struck up from the web and interposed between the flanges thereof, and welded to each other and the flanges.

8. As an article of manufacture, a metal beam of channel section having a series of circular reinforcing members secured to the web and interposed between and secured to the flanges thereof.

9. As an article of manufacture, an integral airplane rib made from sheet material comprising a web, longitudinal marginal flanges struck up at an angle thereto and circular reinforcing members struck up 50 from the web and interposed between and in contact with said flanges.

10. As an article of manufacture, an integral airplane rib made from sheet material comprising a web, longitudinal marginal flanges struck up at an angle thereto and arch-shaped reinforcing members struck up from the web and in contact with and interposed between said flanges.

11. As an article of manufacture, an integral airplane rib made from sheet material comprising a web, longitudinal marginal flanges struck up at an angle thereto and reinforcing members struck up from the web and interposed between and welded 65 to said flanges.

In testimony whereof I hereunto affix my signature.

WILLIAM B. STOUT.
